US00D735378S

(12) **United States Design Patent**
Mozdzer

(10) **Patent No.:** **US D735,378 S**
(45) **Date of Patent:** **** Jul. 28, 2015**

(54) **NIGHTLIGHT**

(71) Applicant: **Hubbell Incorporated**, Shelton, CT (US)

(72) Inventor: **Mark A. Mozdzer**, Derby, CT (US)

(73) Assignee: **HUBBELL INCORPORATED**,
Shelton, CT (US)

(**) Term: **14 Years**

(21) Appl. No.: **29/485,832**

(22) Filed: **Mar. 24, 2014**

Related U.S. Application Data

(62) Division of application No. 29/449,668, filed on Mar. 15, 2013, now Pat. No. Des. 704,869.

(57) **CLAIM**

The ornamental design for a nightlight, as shown and described.

DESCRIPTION

FIG. 1 is a perspective view of a nightlight showing my new design;

FIG. 2 is a top view of the nightlight of FIG. 1;

FIG. 3 is a right side view of the nightlight of FIG. 1;

FIG. 4 is a left side view of the nightlight of FIG. 1;

FIG. 5 is a front view of the nightlight of FIG. 1;

FIG. 6 is a rear view of the nightlight of FIG. 1; and,

FIG. 7 is a bottom view of the nightlight of FIG. 1.

1 Claim, 3 Drawing Sheets
